LAMP LENS FOR AUTOMOBILES OR THE LIKE

George W. Walker, Bloomfield Hills, Mich., assignor to
Ford Motor Company, Dearborn, Mich., a corpora-
tion of Delaware

Application June 13, 1958, Serial No. 51,338

Term of patent 7 years

(Cl. D48—32)

Fig. 1 is a front elevational view of a lamp lens for automobiles or the like, showing my new design;

Fig. 2 is a side elevational view thereof;

Fig. 3 is a rear elevational view thereof;

Fig. 4 is a sectional view taken on the plane indicated by line 4—4 of Fig. 1;

Fig. 5 is an enlarged fragmentary view taken substantially of the portion within the circle 5 of Fig. 4. I claim:

The ornamental design for a lamp lens for automobiles or the like, substantially as shown.
